LIQUID FUEL BURNING INSTALLATION

Hendrik Arnold Romp, Voorburg, Netherlands,
assignor to Shell Development Company, San
Francisco, Calif., a company of Delaware

Application February 8, 1935, Serial No. 5,535
In the Netherlands February 15, 1934

3 Claims. (Cl. 122—1)

The invention relates to liquid fuel burning installations of comparatively small capacity, such as in use, for example, for boilers of central heating installations. The object of the invention is to provide an installation which makes no high demands upon the fuel to be burned therein and is specifically suitable for burning mineral oil residue, i. e. the non-distillable or not readily distillable part of mineral oil very rich in 5 strongly carbonizing substances, such installation being moreover simple and relatively inexpensive.

For burning such heavy fuel practically only the steam injection burner can be considered, in which, as is known, even very heavy residue can easily be burnt free of soot. This is due to the fact that the steam has, besides the mechanical atomizing action, also a chemical action, viz. the conversion of the soot, formed as a result of a local shortage of air, at temperatures above 15 900° C., particularly at temperatures ranging between 1200° and 1750° C., into carbon monoxide and hydrogen, which gases are then burnt without smoke at a sufficient air supply.

Attempt has been made to remove the drawback of a steam-boiler being required for this kind of burners by adding to the latter special arrangements for developing steam by the heat of the flame. The fact that the burners of this category—to which belong also those according to the invention—are yet being used so little in spite of the excellent results obtained in burning heavy oils, has to be mainly ascribed to the following three drawbacks:

1. The rate of outflow of the steam has a 35 tendency to show periodical fluctuations, the so-called pulsation, resulting, during the moments of weak outflow, in a poor atomization of the oil and an insufficient amount of air being sucked in, as a consequence of which the combustion is incomplete with a strongly sooty flame. On the other hand during the moments of strong outflow too much steam and air are blown into the flame, whereby the latter is frequently extinguished, thus causing the danger of explosions at 40 subsequent ignition. The pulsation of the outflow of steam renders an accurate adjustment impossible and gives unsatisfactory combustion.

2. The pressure of the steam in these burners cannot be higher than that at which the water 45 is fed. As is well known a direct connection to the water mains is expressly prohibited by the majority of the public utilities, but even when allowed the required adjustment to a constant pressure, owing to the small consumption of water by the burner, causes a much larger water con-

sumption than corresponds to the amount of steam developed. When using an open constant level tank the steam pressure available is only that corresponding to the difference in height between the constant level tank and the burner; 5 seeing that in this respect one is bound in practice to certain limits, the steam pressure is comparatively low, so that—unless special arrangements are made—the atomization and consequently also the combustion is poor. 10

3. When using water from the mains the channels and reservoirs, in which the steam is developed, are usually clogged very quickly owing to the formation of boiler scale, which soon gives rise to interruptions in the operation or unsatisfactory efficiency. 15

The manner in which these three difficulties have been overcome according to the present invention particularly by the construction of the steam generating installation, is shown in the 20 following description, where a hotwater boiler of a central heating installation has been chosen as an example.

The drawing shows in sectional elevation my invention applied to a hot water boiler of known 25 construction. Referring to this drawing.

A is the hot water stove of a central heating installation of one of the types usually applied for the use of solid fuels. 1 is the grate, 2 the ash-pit door, 3 the fire door, 4 the flue pipe and 30 5 a plate for guiding the gases.

The burner proper B extends into the opening for the fire door 3 and comprises a reservoir 6 filled with a boiling liquid on top of which a condenser 7 with cooling fins 8 is placed. Once the 35 burner is in normal operation the flame heats the underside of the reservoir 6 to such an extent that the liquid contained in it boils, so that the temperature of 6 is maintained constant. The heat from condensation of the vapours of the 40 boiling liquid is given off by the cooling fins to the combustion air sucked in through the opening 9. In this manner this heat also promotes the combustion process.

In the reservoir 6 a coil 11, 12, for generating 45 steam is mounted. The necessary water comes from the tank C installed at a level a few metres higher than the burner, passes a non-return valve 10 preventing reflux of the water to C and subsequently enters a spiral 11 of downward coils 50 in which it evaporates, after which it ascends through a spiral 12 of upward coils.

In the arrangement as described a pulsating outflow of the steam is further avoided by the observation of the following points: 55

1. The temperature of the evaporation member is always constant, i. e. equal to the boiling temperature of the liquid in 6, in contradistinction to other burners, whereby the temperature of the evaporation member has to be maintained by the direct heating of the flame and the inevitable fluctuations in the temperature of the steam by direct heating give rise to an irregular feeding of water and an irregular outflow.

10 2. The volume of the steam space and the amount of water in the evaporation member are reduced to a minimum, so that an extremely small quantity of water fed in excess already brings about an increase of pressure, whereby 15 the non-return valve shuts off the water supply. If the steam space were larger, then in a similar case there would be a longer interval between the commencement of the increase of pressure and the closing of the valve. The later the valve is 20 closed, the more water is fed in excess, the higher the pressure continues to rise after the closing of the valve and the longer the valve has to be kept closed as a corrective measure. This constitutes an important element in the phenomenon 25 of pulsating.

Of course the non-return valve should be constructed so light that it closes readily with a very small pressure difference, whilst it should further be located as close as possible to the spiral 11.

30 In order to prevent pulsating it is necessary that the "inertia" of the aggregate consisting of evaporating element and non-return valve is as small as possible.

However, if water from the mains were used 35 an installation with so small a steam space would soon become clogged-up by boiler scale; with the installation according to the invention the formation of boiler scale is therefore avoided by feeding distilled water to the burner, which is obtained by means of the heat from the installation itself.

On the stove A a closed reservoir E is situated 40 filled with water through pipe 21 from the water mains. The level of water in the reservoir is kept constant by means of a float valve 22. This water is heated by the burnt gases and the water vapour developed escapes through the line 16 extending from above the liquid level and led through the flue in order to avoid condensation.

50 At a little distance above the tank C the line 16 leaves the flue and the water vapour is condensed in the air-cooled sloping condenser 17. The distilled water runs into C. A possible excess of water flows back to C through the overflow line 18 extending to below the water level in E.

55 The result of this arrangement is not only that the burner operates with distilled water but also that the heating of E can be adjusted in such a manner that C is always filled up to the overflow, so that the generator coils 11, 12, are always fed with water at a constant pressure.

The formation of boiler scale now takes place in the reservoir E, which should therefore be cleaned, say, once per season.

The oil is contained in a tank D installed at a level a few metres higher than the burner and 5 flows through the line 19 to the burner nozzle 13, where it is atomized by means of the steam from the spiral 12, mixed in the mixing cone 14 with the combustion air entering at 9 and burnt in the combustion chamber 15 lined with fireproof 10 material. In order to be able to control the size of the flame, the passage of steam and that of oil in the burner nozzle are adjustable by means of valves 23 and 24 respectively.

Since on account of practical reasons it is im- 15 possible to place the water tank much more than 5-7 metres above the burner, it is evident that the atomization by the steam takes place at a pressure which, in view of the resistance in the spirals 11 and 12, at full load certainly will not 20 exceed 0.5 at.

What I claim is:

1. In a steam generating apparatus the combination comprising a heated liquid bath, a coil immersed in said bath, a water receptacle connected to said coil at one end of said coil said water receptacle being mounted at an elevation higher than said coil, a condenser discharging into said water receptacle, a water vaporizer connected to the inlet side of said condenser, an 30 overflow pipe from said water receptacle to said water vaporizer and a conduit leading from the other end of said coil for a connection to an oil burner.

2. In a steam generating apparatus the combi- 35 nation comprising a constant temperature liquid bath, a coil immersed in said bath, a condenser for condensing vapors arising from said bath, a water receptacle connected to said coil at one end of said coil, said water receptacle being mounted 40 at an elevation higher than said coil, a condenser discharging into said water receptacle, a water vaporizer connected to the inlet side of said condenser and a conduit leading from the other end of said coil for connection to an oil burner. 45

3. In a steam generating apparatus the combination comprising a constant temperature liquid bath, a coil immersed in said bath, a condenser for condensing vapors arising from said bath, a water receptacle connected to said coil at one end 50 of said coil, said water receptacle being mounted at an elevation higher than said coil, a condenser discharging into said water receptacle, a water vaporizer connected to the inlet side of said condenser, an overflow pipe from said water receptacle to said vaporizer and a conduit leading from the other end of said coil for connection to an oil burner. 55
